UNITED STATES PATENT OFFICE.

JOHN EDWARD NORMAN, OF LEICESTER, ENGLAND.

DUPLICATOR.

Application filed May 10, 1923. Serial No. 637,951.

To all whom it may concern:

Be it known that I, JOHN EDWARD NORMAN, subject of the King of Great Britain, residing at Leicester, in the county of Leicester, England, have invented certain new and useful Improvements in or Relating to Duplicators, of which the following is a specification, reference being had therein to the accompanying drawing.

10 This invention relates to duplicators which are employed for the purpose of producing copies of written or printed matter and it embodies improvements designed for the purpose of facilitating and simplifying

15 the holding together of the several elements or component parts of the duplicator during the time it is being used in the production of duplicate copies and for subsequently releasing the said elements or components

20 when it is desired to change or renew any of the latter.

The invention will be more readily understood and appreciated, when, as hereinafter, it is described in reference to particular 25 types of duplicators although it should be understood that these are given as examples and not as indicating that the invention is restricted thereto.

A well known type of duplicator comprises a shallow rectangular tray having an upturned edge on each side and containing within on the bottom thereof a felt or equivalent absorbent pad which is saturated with ink or equivalent and hereinafter designated the ink pad.

Resting on the said ink pad is a thin metallic plate furnished with closely positioned small perforations through which the ink from the ink pad when the usual pressure is applied, can exude.

Over this perforated plate a linen or like porous sheet is placed and when this has become uniformly charged with the ink extruded from the perforated plate, a stencil 45 usually consisting of a waxed sheet, is placed thereover.

The matter, of which copies are to be made is generally produced upon the stencil by a typewriter or by a stylo in the manner well understood, the ink from the porous sheet penetrates through the stencil at the parts from which the wax has been removed

by the typewriter or stylo and when a plain blank sheet is placed thereover and pressure applied to it, as for example by passing a 55 hand roller over it, the copy of the stencil is transferred to the plain sheet as will be understood.

It is for the purpose of locking or holding together the hereinbefore-mentioned 60 elements or components of the duplicator that the present invention is designed thereby preventing them becoming disturbed in their relation to each other either accidentally or as the result of manipulation during 65 the time the copies are being produced.

According to the invention the locking and releasing means for the components of the duplicator comprise a rod or equivalent 70 extending across one or each end of the said components arranged in bearings at its opposite ends so that it can be rotated and operate with an eccentric movement to clasp and release the components the distinguishing feature being that said rod or equivalent 75 is mounted in such a manner that it can be readily detached from its bearings without disturbance of the latter and removed from the duplicator.

I am aware that in connection with loose-leaf books, files, temporary binders, paper holders and the like, a clamp consisting of a rotatable eccentric, eccentrically mounted roller or similar cam device mounted in a frame or holder has been proposed and I do 80 not therefore claim any such device per se. In the former suggested arrangements however, the rotatable eccentric clamp device has not been adapted for removal without detachment or disturbance of at least one 85 of its bearings. My invention concerns the application of a clamp device of such known form to a duplicator, the novelty residing in the means I adopt for permitting ready detachment of the device from its bearings 90 in order that it may, when desired, be removed from the duplicator, such for example as to permit removal of the components from the tray or arrangement of the same therein.

100 In order that my invention may be clearly understood reference will now be made to the accompanying drawing which shows some practical examples thereof.

Figure 1 is a plan of a duplicator having a convenient and the preferred form of the invention applied thereto.

Figure 2 is a transverse section on the line *a—a* of Figure 1.

Figure 3 is an elevation of an alternative form of the locking means.

Figure 4 is an end view of the locking element.

Figure 4 is drawn to a larger scale than the rest of the figures, and like parts are designated by the same reference characters in the several figures.

A duplicator of the known type previously described herein is depicted in Figures 1 and 2, where 1 is the shallow rectangular tray with upturned edges, 2 is the felt or equivalent absorbent pad, 3 is the thin metallic perforated plate and 4 is the linen or like porous sheet upon which the stencil (not shown) is placed.

For firmly holding the absorbent pad, perforated plate, porous sheet and stencil in position in the tray, locking means are provided and comprise a rod 5 extending across one or each end of the said elements and formed integrally therewith or attached to each end thereof is a projecting pin 6 out of concentricity with the axis of said rod. Bearings are formed in the tray for the said eccentric pins which may conveniently take the form of holes 7 formed in the upstanding edges of the tray or alternatively they may consist of upright bearings, pillars or the like connected to said tray. A stud, pin or equivalent 8 is rigidly secured to the rod 5 at a point intermediate of its ends, so that its position is within the duplicator, and can be readily moved through an arc of a circle to operate the rod to bear and exert a downward pressure upon the said elements to lock or clamp them, and also to release the pressure upon the said elements so that they can be manipulated as may be necessary.

As a modification, instead of mounting the locking and releasing rod eccentrically in its bearings it may be mounted concentrically therein, in which case it takes the form of the rod 6^a shown in Figure 3 and has eccentrics 5^a fast upon it at intervals apart to exert pressure upon the parts to be held when the said rod 6^a is given a partial rotary movement by means of the stud 8. In end view the locking means shown in Figures 2 and 3 are the same as represented in Figure 4.

The invention consists in a construction and arrangement of the pressure rod so that it can be readily detached from its bearings and from the duplicator when it is desired to do so.

In the preferred arrangement, the journal pins 6 on the opposite ends of the rod 5

in the construction shown in Figures 1 and 2, and the opposite ends of the rod 6^a in the construction shown in Figure 3, are of different lengths as shown so that an endwise movement of the said rod will effect the positioning or removal of the rod from its bearing. For instance, when placing the rod in position the longer pin or end is first inserted in its bearing and then by an endwise movement of the rod the shorter pin can also be passed into its bearing which in each case is formed in the shape of an eye or circular aperture. To remove the rod from the tray it is moved endwise towards the right to disengage the shorter pin or end from the bearing and then it is lifted and withdrawn from the other bearing by an endwise movement to the left.

While the invention has been hereinbefore described in reference to a particular type of duplicator it is not intended that it shall be limited thereto, as it may equally well be applied to other types of duplicators in which a series of superposed flat elements are employed. For example it may be applied to a duplicator of the kind comprising a flat metal plate or holder, a series of blank sheets superposed and interleaved with carbon sheets and a top blank sheet upon which the matter is written by a pencil or stylo so that corresponding copies are produced upon the intervening blank sheets by pressure of the pencil or stylo upon the interleaved carbon sheets as is well understood.

What I claim then is:—

1. In a duplicator of the type wherein a plurality of components or elements of the kind herein referred to require to be held together, locking and releasing means for said components comprising a clamp member extending across the components, and arranged in bearings at its opposite ends so that it can be rotated and operate with an eccentric movement upon the components, said clamp member being provided with journal pins of different lengths at its opposite ends for permitting its insertion and removal into and from its bearings.

2. In a duplicator of the type wherein a plurality of components or elements of the kind herein referred to require to be held together, locking and releasing means for said components comprising a rod extending across the components arranged in bearings at its opposite ends so that it can be rotated and operate with an eccentric movement to clamp and release the components, said rod being provided with journal pins of different length at its opposite ends for permitting insertion and removal of the rod into and from its bearings.

In testimony whereof I affix my signature.

JOHN EDWARD NORMAN.
